UNITED STATES PATENT OFFICE.

WILLIAM W. LANGLEY, OF UNION CITY, OHIO, ASSIGNOR OF ONE-HALF TO
HENRY REITENOUR AND GEORGE W. REITENOUR, OF SAME PLACE.

KITCHEN-CABINET.

SPECIFICATION forming part of Letters Patent No. 327,801, dated October 6, 1885.

Application filed May 2, 1885. Serial No. 164,257. (No model.)

To all whom it may concern:

Be it known that I, WILLIAM W. LANGLEY, of Union City, in the county of Darke, in the State of Ohio, have invented a new and useful Improvement in Kitchen-Cabinets; and I do hereby declare that the following is a full and exact description thereof, reference being had to the accompanying drawings, and the letters and figures of reference marked thereon.

My invention relates to improvements in kitchen-cabinets, and is designed to produce a device that shall combine in a small and convenient space receptacles for various articles—such as materials used in cooking and the utensils necessary for the same; also, extensible racks and other points of utility, as hereinafter specified.

In the drawings, Figure 1 represents a front elevation of the device; Fig. 2, a side elevation with parts shown in dotted lines; Fig. 3, a vertical section from front to rear with bins and shelf extended; Fig. 4, a plan view of the upper section with top removed, and Fig. 5 a side view of the extensible rack.

A suitable frame is provided with an upwardly-extending back, H, carrying some what above the top of the cabinet a shelf, J.

To the rear of the back are vertical strips H', to which are pivoted strips I', on a rack, I. This rack is provided with pins, on which may be hung any articles desired. The rack is normally held in an upright position by buttons i on the strips H', and may be thrown backward and downward against the lower portion of the back of the cabinet when not in use.

The top or cover A is connected to the frame at the front of the cabinet by a hinge, E, the portion or half of which that connects with said table being angular, so as to allow the said top, when thrown outward and downward, to rest below the surface exposed on top the cabinet-frame. When closed the sides of the top have the tenons G in their ends, engage in mortises G' in the brackets supporting the shelf J, and forming a part of the back. A view of each of these portions G and G' are shown in detail appended to Fig. 3. The mortise-and-tenon joint serves to stiffen and strengthen the top when closed.

The top A, when open, is held in a horizon-

tal position by an extensible stay-rod consisting of the part B pivoted to the said top and having an eye at its free end, and a part, B', 55 similarly formed, the eyes of each receiving the main portion of the other and pivoted to the frame. The part B' is bent at about right angles before reaching the pivotal point, whereby the shoulder b is formed, causing the 60 said part to rest a short distance away from the frame. As the top is opened outwardly the parts B and B' will travel on each other, whereby the said stay-rod is extended. When in a horizontal position the eye on the part B 65 rests on the shoulder b and holds the said shelf or top.

The bottom of the top A has on it lateral strips C, which, when the top is opened outward, prevent the loss of material—say, of flour 70 in bread-making—by its falling therefrom.

Within the lower portion of the cabinet is contained the bin-frame D, of a general rectangular or more nearly square form in cross-section, as in Fig. 3. The bin-frame may be 75 divided into as many compartments as is desirable.

Through each end, near one corner of the bin-frame, passes the pivotal bolt or screw K, supported at the inner end by a hanger, L, 80 suspended from the bottom of the upper section of the body of the cabinet. The position of the pivot permits the rear of the bin to be made much higher than if otherwise placed, at the same time, when open, engaging with the 85 bottom of the section F, which thereby acts as a stop. The bins can thus be opened, as shown in Fig. 3, without projecting to too great an extent.

When the bins are open, the contents of the 90 table may be emptied into them by placing said table in an upright position, the hinge causing a space between the said table and the frame to which it is pivoted.

The section F may be provided with a series 95 of compartments, m.

Under the shelf J is located a rack, N, consisting of two lazy-tongs with a portion of the arms extended or prolonged, as at n, Fig. 5, and bars connecting said extensions. One end 100 of the said lazy-tongs is pivoted in suitable bearing-pieces, O. This forms a convenient towel or other rack, that will be entirely out of the way under the shelf J when not in use.

The operations of the various parts having been set forth, in conjunction with the description of the construction, it will not be repeated.

5 The bin is so constructed that when closed the back thereof forms a portion of the back of the cabinet, as is evident from Fig. 3.

The pivotal point of the bin, when closed, is well toward the front, and in no instance does it go beyond the center, thus facilitating the closing thereof, and preventing accidental opening thereof, special advantages not possessed by such bins as have the pivotal point at or below the bottom, or at some 15 distance above the bottom, but centrally located.

I am well aware that it is not broadly new to use a hinged top supported, when opened, by jointed hangers; hence my invention does 20 not broadly cover such construction, nor the manner of pivoting the bins as above set forth.

I claim—

1. A kitchen-cabinet having a bin of general rectangular shape, hung pivotally by 25 means of bolts passing through the sides of

said cabinet and through the ends of the bin near one corner thereof, said bolts having their inner ends supported by hangers secured to the cabinet-frame, substantially as and for 30 the purpose specified.

2. A kitchen-cabinet having a suitable frame, and a top hinged thereto by means of angle-hinges, and supports or stays for said table, consisting of pivoted rods sliding one 35 on the other, substantially as and for the purpose specified.

3. A kitchen-cabinet having a suitable frame, a top hinged thereto by angle-hinges, sides for said top, having tenoned ends fitting 40 mortises in the frame, and supports or stays consisting of rods pivoted, respectively, to the table and to the frame and sliding one on the other, substantially as and for the purpose specified.

WILLIAM W. LANGLEY.
